PUMP

William A. Jones, Stamford, Conn., assignor to
American Cyanamid Company, New York, N. Y.,
a corporation of Maine

Application June 25, 1941, Serial No. 399,587

12 Claims. (Cl. 103—149)

The present invention relates to a pump mechanism.

The principal object of the invention is to provide a device of the above character capable of delivering uniform quantities of liquid intermittently.

Another object of the invention is to provide a pump in which the amount of liquid delivered at each impulse may be accurately controlled and which amount may be adjusted at will through wide limits, even while the device is in operation.

Another important object is to provide a device of the above character which is sturdy in construction, compact in arrangement, capable of being easily cleaned and which has few parts to get out of order.

The invention in its broadest aspect contemplates a pump of the Huber type for receiving liquid from a supply and moving it to a point of delivery with means for intermittently operating the pump so as to deliver varying quantities of liquid to the desired point.

The Huber pump comprises generally a length of collapsible tubing held within a casing having an inner wall with a plurality of rollers mounted for continuous contact with and collapsing the tubing against the inner wall. Thus, as each roller progresses along the tubing, it forces liquid ahead of it to the outlet where the liquid is discharged.

The intermittent operating mechanism of the present invention constitutes a prime mover such as an electric motor or the like with or without the usual speed reducing mechanism, with a varying throw connecting rod constituting the mechanical connection between the prime mover and an oscillating arm serving to cause rotation of the squeezing roller in an intermittent manner. Inasmuch as both ends of the connecting rod are adjustable, the extent of its throw may be readily controlled even while the device is in operation, to adjust the amount of liquid delivered by the pump.

The invention further consists in the novel construction, arrangement and combination of parts more fully hereinafter described and shown in the accompanying drawings, in which—

Fig. 1 is a front view of a device embodying the present invention;

Fig. 2 is a view along the line 2—2 of Fig. 1, partly in section;

Fig. 3 is a rear view of the device of Fig. 1;

Fig. 4 is a detail view showing the manner of removal of the tube casing;

Fig. 5 is a view along the line 5—5 of Fig. 4; Fig. 6 is a perspective detail of the casing proper;

Fig. 7 is a side view of a modified assembly; and

Fig. 8 is a sectional view along the line 8—8 of Fig. 7.

Referring now with particularity to the devices illustrated, a frame is shown generally at 1 upon which is mounted a prime mover 2, such as an electric motor or the like, supplied with current from a suitable source (not shown) and having a standard type of speed reducing mechanism enclosed within a housing 3.

An eccentric crank 4 is driven by the motor and carries a stub shaft 5 terminating in a block 6 and held within a radially-extending, guiding slot in the eccentric 4. The block 6, carrying the stub shaft 5, may be moved in this slot by means of the threaded shank 7 which passes therethrough, and terminates in knurled head 8.

A connecting rod 9 is fitted at one end to the stub shaft 5 and held thereon by means of knurled nut 10 and at the other end is pivoted as at 11 to a guiding block 12. The block 12 rides within a hollow oscillating arm 13 and is carried by a threaded rod 14. This rod is fixed within a journal member 15 through which it passes, by means of collar 16 and knurled adjusting knob 17. The oscillating arm 13 is clamped within an extension of the journal 15. Thus rotation of the knurled adjusting knob 17 causes movement of the guiding block 12 within oscillating arm 13 and consequently, determines the extent of the throw of the connecting rod.

The journal and clamping extension 15 is mounted on a fixed stud 18 of the frame 1, through which the pump shaft 19 passes.

A clutch or intermittent movement control connection, preferably of the over-riding type, is provided between the journal 15 and the pump shaft 19 and this mechanism includes a rotor 20 keyed to the pump shaft 19 and containing notches 21, in each of which is located a roller 22. The rotor 20 fits closely within the journal 15 and moves with the shaft 19.

From Fig. 3 it will be seen that when the journal 15 moves in a counterclockwise direction, the rollers 22 also move in a counterclockwise direction or into the widest portion of the notches 21 with the consequence that rotation of the journal 15 does not transmit its movement to the pump shaft 19. Rotation of the journal 15 in a clockwise direction causes rollers 22 to be moved clockwise and into the narrower portions

of their notches under the impulse of coil springs 23, thus making a wedge connection between the rotor 20 and the journal 15. As a result, the shaft 19 is driven in a clockwise direction by the journal 15.

Thus, rotation of the eccentric 4 causes oscillation of the arm 13 through the connecting rod 9 and through the clutch mechanism intermittent clockwise movement of the shaft 19.

The pump mechanism proper includes a casing indicated generally at 24 having a substantially rectangular rear wall 25. The casing 24 is mounted on the frame 1 with its lower extensions 26 seated upon a pair of positioning supports 27 and held there by means of upper and lower pairs of retaining ears 28 on the frame, which engage the front of the rear wall 25 of the casing. These parts are so arranged that when the casing is in position, its center will accurately coincide with the center of shaft 19.

On the pump shaft 19 is mounted a rotary wall 29 carrying a stub shaft 30 provided with a ball bearing mounted roller 31. From Fig. 2, it is to be noted that the inner surface of the rotating wall 29 is substantially flush with the inner face of the casing 24 and that the upper edge of the circumference of the roller 31 is spaced slightly from the cylindrical inner wall of the casing.

A convolution of collapsible tubing 32 is arranged within the casing having an inlet portion 33 and a delivery portion 34, the roller and tubing being so positioned that the tubing is completely collapsed between the roller and the inner wall of the casing. Consequently, as the roller rotates in a clockwise direction (Fig. 1), liquid within the tubing between the roller 31 and the delivery end 34 is moved toward the outlet in an intermittent manner, inasmuch as the roller is intermittently moved. At the same time, liquid within that portion of the tubing 33 follows along behind the roller so as to keep the tubing full of liquid.

It will be seen that any desired size of tubing may be used, it being only necessary to change the size of the roller 31 where tubing of different wall thicknesses are used.

As the inlet portion of the tubing 33 is held within an aperture 35 and the delivery end 34 within an aperture 36, the tube is accurately held in place. It is desirable to lubricate the surface of the tube so that the roller 31 will not create a tendency of the tube to creep.

If for any reason it is desirable to remove the casing with its contained tubing for replacement, repair or adjustment, the lever 37 is moved from the position shown in Fig. 1 to that of Fig. 4 with the result that the cam 38 is released from the top of the rear wall 25 of the casing. Under the impulse of coil spring 39 (Fig. 2), the finger 40 pushes the casing 24 upwardly into the position shown in Fig. 4. The recesses 41 in the rear wall 25 of the casing permit clearance of the retaining ears 28 and the casing may be then withdrawn in a forward direction. The casing may be replaced by reversing the above operation.

A knurled hand wheel 42 is secured to the outer end of the pump shaft 19 adjacent the rotor 20 for the purpose of setting the position of the roller 31, since it is necessary that this roller be located at the upper end of its stroke when the rubber tube assembly is removed or replaced. This position, illustrating the clearance between the roller and the rubber tubing is shown in Fig. 4.

From the above, it will be seen that a com-

5 pound crank mechanism is provided between the prime mover and the pump shaft 19 for moving the latter intermittently. The adjusting knobs 8 and 17 permit adjustment of the throw and this compound crank, thus determining the feed of liquid through the outlet 34 of the tubing.

10 For instance, adjustment of the upper knurled head 8 makes possible the movement of the upper end of the connecting rod 9 from dead center on the eccentric, where no feed will result, out to its outer edge. This, therefore, permits of the finest type of adjustment and makes possible with a suitable sized tubing, a feed of even so small a quantity as a fraction of a drop.

15 Adjustment of the knurled knob 17 at the journal 15 will determine the relative position of the lower end of the connecting rod 9 and consequently, the degree of oscillation of the arm 13. For instance, when the end of the connecting rod 20 is in the position shown in Fig. 1, it will have considerably less movement than it would in the position shown in Fig. 3.

20 Thus between the two adjusting nuts, any degree of movement of the roller 31 may be obtained upon a single revolution of the eccentric 4.

25 In Figs. 7 and 8, a slightly modified form of assembly is shown.

30 Here the connecting rod 9 is attached at its lower end to an oscillating arm 43 mounted directly on the fixed stud 18 without adjustment means at this point. The same type of clutch mechanism is shown as has been previously described for making an intermittent driving connection between the oscillating arm 43 and the pump shaft 19.

35 In the present modification, however, the casing which contains the collapsible tubing is of slightly different form. It is indicated generally at 44 as being in effect a part of the base 1 and also serving to support the prime mover 2. As shown, the casing has an inner surface 45 against which one or more lengths of rubber tubing 46 and 47 lie. The tubing is held in place by means of clamps 48.

40 The pump shaft 19 has mounted thereon on the pump side of the device, a rotating rear wall 49 on which is eccentrically mounted a plurality of tubing squeezing rollers 50 and 51. These rollers are so arranged with relation to the inner surface 45 of the casing and the thickness of the tubing used, that as the rear wall 49 rotates the tubing will be completely collapsed between the roller and the inner wall and that there will always be a roller in collapsing contact with the tube. Consequently, a flow of liquid through the tube may always be obtained so long as the rear wall is being rotated in a pumping direction.

45 The casing is provided with a front plate 52 having a series of ears 53 engaging screw threaded studs, the wall being held in place by suitable nuts 54.

50 While two lengths of tubing are shown, yet any number can be used, dependent upon the depth of the casing and the size of the tubes. Where a plurality of independent lengths of tubing are used as shown, it permits of a multiple feed device which is sometimes desirable.

55 It will be noted that the tubing may be removed by simple removal of the front wall 52 and loosening of the clamp members 48. It will also be seen that in the same way the rollers 50 and 51 can be removed from their stub shafts 30, at this time, as the front wall 52 serves to hold them in place.

The device of the invention may be successfully used to feed liquids of any character in a uniform manner regardless of viscosity, temperature or specific gravity. This is particularly desirable where, for instance, reagents are being fed to a reaction menstruum where an adjustment once fixed, should not be changed through mere temperature changes.

Again, such a device is particularly desirable in the feeding of accurate amounts of very small quantities, such for instance, as perfumes or biological products into ampules or the like. In such cases, fractions of drops may readily be accurately delivered by the simple expedient of restricting the outlet end of the tube 34 as by means of a glass tip or the like (not shown). On the other hand, the device may be adjusted to deliver much larger quantities of liquid where desired.

While the invention has been shown and described with particular reference to specific embodiments, it is to be understood that it is not to be limited thereto, but is to be construed broadly and restricted solely by the scope of the appended claims.

I claim:

1. A pump comprising a length of collapsible tubing held within a casing having an inner surface, said casing having a rotatable wall, a roller eccentrically mounted on said wall and making contact with and collapsing the tubing against the casing surface, a shaft for rotating said wall and means for intermittently rotating the shaft in one direction including an over-run clutch.

2. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover for rotating the shaft and a clutch between the prime mover and the shaft for intermittently rotating the latter.

3. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover, an over-run clutch between the shaft and prime mover, and a compound crank mechanism connecting the prime mover with the shaft.

4. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover, an over-run clutch between the shaft and prime mover, and a compound crank mechanism connecting the prime mover with the shaft and means for adjusting the throw of the crank mechanism.

5. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover, an over-run clutch between the shaft and prime mover, and a compound crank mechanism connecting the prime mover with the shaft, said compound crank including an eccentric and a connecting rod, the eccentric connecting the prime mover with the connecting rod.

6. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover, an over-run clutch between the shaft and prime mover, and a compound crank mechanism connecting the prime mover with the shaft, said compound crank including an eccentric and a connecting rod, the eccentric connecting the prime mover with the connecting rod and means to adjust the relationship of the connecting rod to the eccentric, for varying the movement of the rod.

7. A pump comprising a length of collapsible tubing held within a casing having an inner surface, said casing having a rotatable wall, a roller eccentrically mounted on said wall and making contact with and collapsing the tubing against the casing surface, a shaft for rotating said wall, a prime mover, an over-run clutch between the shaft and prime mover, and a compound crank mechanism connecting the prime mover with the shaft, the compound crank mechanism including a connecting rod, a rotatable eccentric between the prime mover and one end of the connecting rod, and an oscillating arm between the shaft and the other end of the connecting rod.

8. A pump comprising a convolution of collapsible tubing held within a casing having an inner cylindrical surface, said casing having a rotatable wall, a roller eccentrically mounted on said wall and making contact with and collapsing the tubing against the cylindrical surface, a shaft for rotating said wall, a prime mover, an over-run clutch between the shaft and prime mover, and a compound crank mechanism connecting the prime mover with the shaft, the compound crank mechanism including a connecting rod, a rotatable eccentric between the prime mover and one end of the connecting rod, and an oscillating arm between the shaft and the other end of the connecting rod and means adjacent each end of the connecting rod for adjusting its throw.

9. A pump comprising a convolution of collapsible tubing held within a casing having an inner cylindrical surface, said casing having a rotatable wall, a roller eccentrically mounted on said wall and making continuous contact with and collapsing the tubing against the cylindrical surface, a shaft for rotating said wall, a prime mover, an over-run clutch between the shaft and prime mover, and a compound crank mechanism connecting the prime mover with the shaft, the compound crank mechanism including a connecting rod, a rotatable eccentric between the prime mover and one end of the connecting rod, and an oscillating arm between the shaft and the other end of the connecting rod and means adjacent each end of the connecting rod for adjusting its throw.

10. A pump comprising a convolution of collapsible tubing held within a casing having an inner cylindrical surface, said casing having a rotatable wall, a roller eccentrically mounted on said wall and making continuous contact with and collapsing the tubing against the cylindrical surface, a shaft for rotating said wall and means for intermittently rotating the shaft in one direction including an over-run clutch.

11. A pump comprising a convolution of collapsible tubing held within a casing having an inner cylindrical surface, said casing having a rotatable wall, a roller eccentrically mounted on said wall and making continuous contact with and collapsing the tubing against the cylindrical surface, a shaft for rotating said wall, a prime mover for rotating the shaft and a clutch between the prime mover and the shaft for intermittently rotating the latter.

12. A pump comprising a length of collapsible

tubing held within a casing having an inner surface, said casing having a rotatable wall, a plurality of rollers eccentrically mounted on said wall and so arranged that there will always be at least one roller making contact with and collapsing the tube against the casing wall, a shaft for rotating said walls and means for intermittently rotating the shaft in one direction including an over-run clutch.

10

WILLIAM A. JONES.
